US0D1071930S

(12) **United States Design Patent** (10) Patent No.: **US D1,071,930 S**
(45) Date of Patent: ** Apr. 22, 2025

(54) **DATA PROCESSING EQUIPMENT**

(71) Applicant: **Kistler Holding AG**, Winterthur (CH)

(72) Inventors: **Thomas Ehrensperger**, Henggart (CH);
Simon Bonadurer, Winterthur (CH);
Isak Lichtenstein, Zurich (CH); **Pascal Boltshauser**, Warth (CH)

(73) Assignee: **Kistler Holding AG**, Winterthur (CH)

(**) Term: **15 Years**

(21) Appl. No.: **35/517,422**

(22) Filed: **Jun. 9, 2022**

(80) **Hague Agreement Data**

Int. Filing Date: **Jun. 9, 2022**

Int. Reg. No.: **DM/221517**

Int. Reg. Date: **Jun. 9, 2022**

Int. Reg. Pub. Date: **Jun. 9, 2023**

(51) **LOC (15) Cl.** **14-02**

(52) **U.S. Cl.**

USPC **D14/358**

(58) **Field of Classification Search**

Assistant Examiner — Megan Tiana Rakos

(74) Attorney, Agent, or Firm — Dority & Manning, P.A.

(57) **CLAIM**

The ornamental design for data processing equipment as shown and described.

DESCRIPTION

1.1 is a perspective view of the data processing equipment.

1.2 is an elevation view of the top of the data processing equipment.

1.3 is an elevation view of the rear of the data processing equipment.

1.4 is an elevation view of the left side of the data processing equipment.

1.5 is an elevation view of the right of the data processing equipment.

1.6 is an elevation view of the bottom of the data processing equipment.

1.7 is an elevation view of the front of the data processing equipment.

Features shown in dashed line are not part of the claimed design and are shown as unclaimed graphics or environmental features.

1 Claim, 7 Drawing Sheets
